UNITED STATES PATENT OFFICE

JUDSON L. MCKELLAR, OF RICHMOND HILL, NEW YORK

CONVERTIBLE CHAIR COUCH

Application filed September 18, 1928. Serial No. 306,748.

This invention relates to convertible chair-couches conveniently used either as a chair or extended to form a full-length couch, the object of the invention being to provide an article of furniture of this class with folding or shiftable arm rests whereby a more practical form of convertible chair couch is obtained than has heretofore been provided, the arm rests being so constructed that they will conform to the different positions of the back when the article is used as a chair, whereby they will be always at the proper height to provide a comfortable article of furniture.

A further object of the invention is the provision of an article of furniture of the class described, simple in construction and which can be inexpensively manufactured and which can be readily converted from a couch to a chair or reclining chair and vice versa, and which in all positions of the article as a chair, the arm rests will be automatically shifted to the proper height to conform to the different positions of the back of the chair, and which arm rests are so located when the back is lowered to form a couch, that they will be entirely out of the way.

I am aware that convertible chair-couches have been patented, as in my Patent No. 1,405,931, dated February 7, 1922, and patent to Luppino, 1,145,777 of July 6, 1915, but neither of these convertible chair-couches are provided with arm rests shiftable or otherwise and consequently, they are just as practical as a chair as an ordinary chair or rocker would be without arm rests and therefore, the object of the present invention is to provide a more practicable, comfortable and commercial article of this type than is disclosed in either of said patents, and to do this in a simple, practical and inexpensive manner whereby the cost of the article will not be materially increased and whereby the user will have all of the advantages of arm rests of whatever form desired in all positions of the article when used as a chair, since the arm rests are so located that whether the back of the article is upright or inclined the arm rests will be automatically positioned according to the height of that back and thus they

are conveniently placed for the arms of the user in all positions of the back.

In the drawings accompanying and forming part of this specification, Fig. 1 is a perspective view of this improved chair-couch with the foot extended;

Fig. 2 is a perspective view thereof when the article is folded into a chair.

Fig. 3 is a plan view of this improved convertible chair-couch in extended form with the cushions thereof removed.

Fig. 4 is a side view thereof with the cushions in dotted position, and

Fig. 5 is a side view of this improved convertible chair-couch illustrating in dotted lines the different positions of the parts thereof.

Similar characters of reference indicate corresponding parts in the several views.

Before explaining in detail the present improvement and mode of operation thereof, I desire to have it understood that the invention is not limited to the details of construction and arrangement of parts which are illustrated in the accompanying drawings, 75 since the invention is capable of other embodiments, and that the phraseology which I employ is for the purpose of description and not of limitation.

This convertible chair-couch in its preferred form comprises a seat section 2 having hinged thereto a front or foot section 3 and also pivotally connected thereto a back section 4. The seat section 2 preferably comprises a suitable framework comprising a pair of front legs 5 and a pair of rear legs 6, each pair being suitably braced, these legs being connected by suitable angle iron members or side bars 7 between which is located a suitable flexible fabric or spring mattress usually made up of suitable links connected with the bars by coiled springs. To the front of this seat section the foot or front section 3 is hinged and this likewise consists of a suitable frame 8 having a similar form of spring or mattress connected to the side bars 9 thereof. This front section is provided with a pair of foldable legs 10 pivoted thereto and each link is connected to the seat section as 11 preferably at the top of the front 100

legs thereof, whereby the foot section may be folded over upon the seat section when the article is to be used as a chair, the link connection 11 being such that the legs of the front or foot section will automatically fold or unfold when the front section is raised or lowered, in which latter position the legs support the front.

Connected to the rear of the seat section is the swinging back section 4, this likewise comprising a suitable framework 12, to the side bars 13, of which a suitable spring mattress is connected in the same manner as with the seat section. In fact, the mattress of the seat section and that of the back section may be made as a single spring mattress, if preferred. The side bars of the back 13 are pivotally connected to the seat section adjacent to the tops of the rear legs 6 thereof, and this back section is likewise provided with a pair of foldable legs 14 pivotally connected thereto and linked by links 15 to the rear legs 6 of the seat section whereby when the back section is raised or lowered the legs 14 will likewise be folded or unfolded, in the latter position of which they serve to support the back when in its lowered position to form a couch.

For the purpose of holding the back in different inclined positions, the links 15 connected with the legs 14 of the back are provided with inwardly extended headed pins or projections 16 adapted to be engaged by a pair of notched bars 17 pivotally connected with the rear legs 6 of the seat, these notched bars projecting forwardly of the legs and connected together, as at 18, to form a treadle, and being connected with the seat by a coil spring 19, whereby on its manipulation the notched bars will be raised to release the pins of the back and permit it to be lowered into different inclined positions and firmly held in any of such positions. The back may be raised to any desired position by merely shifting the back upward.

The shiftable or folding arms each comprise a horizontal bar 20 linked to the front part of the seat section and preferably to the front legs thereof by a link 21 offset adjacent to its lower end, this link being pivotally connected to the front leg of the seat section and to the front end of the arm bar or rest. The rear end of this arm bar or rest is offset, as at 22, and is pivotally connected, as at 23, to the folding rear leg 14 of the back. Thus by this construction, the position of the back and the back supporting legs determines the position of the arm rests so that when these legs are in position to support the back when fully lowered, the arm rests are entirely out of the way and in fact are slightly below the seat so that they do not interfere with the article as a couch, and in this position, they may, because of the location of the pivotal points, be pushed suf-

ficiently far down so as to lock the back in its lowered position, if desired.

Upon raising the back the arms are automatically shifted upwardly and forwardly to correspond in height with the inclination of the back, the arms having their full height when the back is fully raised.

Thus, it will be observed that in this improved convertible chair-couch the arm rests are at the desired height for use in whatever position the back is located, thus providing a very practical convertible chair-couch and not only a practical chair-couch but an ornamental one.

The structure is provided with suitable foldable cushions 24, preferably of book-form construction, the front and seat section of the cushion being provided with a valance 25 at the hinge of the cushions to overlap the front of the chair and give it a decorative appearance, while the back cushion is suitably connected to the top of the back section to maintain this back cushion in proper position, and for this purpose the back section is provided with a head rail 28, and the back cushion is provided at the top rear thereof with a pair of flaps which may be laced around the back and thus maintain the back cushion in proper position.

When the structure is in the form of a couch and it is desired to convert it into a chair, the foot cushion is turned over upon the seat cushion and these two are then raised thereby permitting the foot section 3 to be folded upon the seat section whereupon the cushions are lowered. The back is then raised, thereby automatically shifting the foldable arms into the proper position for use.

The arm rest bars are provided with suitable pads 26 bolted thereto and which are covered by suitable arm rest covers 27 of ornamental fabric.

It is to be understood that by describing in detail herein any particular form, structure or arrangement, it is not intended to limit the invention beyond the terms of the several claims or the requirements of the prior art.

Having thus explained the nature of my said invention and described a way of constructing and using the same, although without attempting to set forth all of the forms in which it may be made, or all of the modes of its use, I claim:

1. A convertible chair-couch comprising a seat section having legs, a swinging back section having foldable legs, and automatically shiftable arm rests connected with the legs and having different positions according to the inclination of the back.

2. A convertible chair-couch comprising a seat section having legs, a swinging back section having foldable legs, means for holding said back section in various inclined positions, and shiftable arm rests connected with the

legs and automatically shiftable with the folding legs of the back into different positions according to the inclination of the back.

3. A convertible chair-couch comprising a seat section having legs, a swinging back section having foldable legs, a shiftable foot section also having foldable legs, and automatically shiftable arm rests connected with certain of said sections below the seat and back when converted into a couch and having different positions according to the inclination of the back.

4. A convertible chair-couch comprising a seat section having legs, a swinging back section having foldable legs link-connected with the rear legs of the seat section, a swinging foot section having legs link-connected with the front legs of the seat section and shiftable arm rests link-connected with the front legs of the seat section and with the foldable legs of the back section and automatically shiftable with the back into different positions according to the inclination of the back.

5. A convertible chair-couch comprising a seat section having legs, a swinging back section having foldable legs link-connected with the rear legs of the seat section, a swinging foot section having legs link-connected with the front legs of the seat section, shiftable arm rests link-connected with the front legs of the seat section and with the foldable legs of the back section and automatically shiftable with the back into different positions according to the inclination of the back, and means for holding the back in different inclined positions.

6. A convertible chair-couch comprising a seat section having legs, a swinging back section having folding legs link-connected with the rear legs of the seat section, means for holding the back section in different inclined positions, a swinging front section foldable on to the seat section and having legs link-connected with the front of the seat section, and automatically shiftable arm rests comprising offset arms pivotally connected with the foldable legs of the back section and linked by offset links with the front legs of the seat section and foldable into different positions according to the inclination of the back.

7. A convertible chair-couch comprising a seat section having legs, a swinging back section having foldable legs link-connected with the seat section, and shiftable arm rests comprising offset bars pivotally connected with the foldable legs of the back section and connected by offset links with the legs of the seat section and shiftable into different positions according to the inclination of the back.

8. A convertible chair-couch comprising a seat section having supporting legs, a swinging back section having foldable supporting legs link-connected with the seat section, means for folding the back into different in-

clined positions and operative to permit the back to be lowered to form a couch, a swinging foot section hinge-connected with the seat and foldable thereonto and provided with foldable legs link-connected with the seat section and shiftable arm rests link-connected to the structure adjacent to and below the front end of the seat section and in the rear of and below the back section when the structure is converted into a couch and automatically shiftable into different positions according to the inclination of the back.

9. A convertible chair-couch comprising a seat section having supporting legs, a swinging back section having foldable supporting legs link-connected with the seat section, means for folding the back into different inclined positions and operative to permit the back to be lowered to form a couch, a swinging foot section hinge-connected with the seat and foldable thereonto and provided with foldable legs link-connected with the seat section and shiftable arm rests link-connected adjacent to the front end of the seat section and in the rear of the back section and automatically shiftable into different positions according to the inclination of the back, said arm rests comprising bars offset at their rear ends, and links connected at their forward ends and offset at their lower ends.

10. A convertible chair-couch comprising a seat section, a swinging back section, a shiftable foot section, means for supporting the several sections and including foldable legs for the front section and the swinging back section, and automatically shiftable arm rests connected to the structure below the seat and back when converted into a couch and raised and lowered according to the inclination of the back and lowered out of the way and below the seat section when the back is lowered to form a couch.

11. A convertible chair-couch comprising a seat section, a swinging back section, a shiftable foot section, means for supporting the several sections and including foldable legs for the front section and the swinging back section, and automatically shiftable arm rests so connected with certain of said sections as to be raised and lowered according to the inclination of the back and be lowered out of the way and below the seat section when the back is lowered to form a couch, and comprising bars pivotally connected to the legs of the back and link-connected to the front legs of the seat.

12. A convertible chair couch comprising a seat, a swinging back pivotally connected with the seat, shiftable arm rests, and a pair of links pivotally connected to the arm rests at opposite ends thereof and pivotally connected with the structure independently of the pivotal connection of the back and seat and adjustable into lowered position when the back is lowered to form a couch.

13. A convertible chair couch comprising a seat, a swinging back pivotally connected with the seat, a shiftable foot, automatically shiftable arm rests, and a pair of links pivotally connected to the arm rests at opposite ends thereof and pivotally connected with the structure independently of the pivotal connection of the back and seat and adjustable into lowered position when the back is lowered to form a couch.
14. A convertible chair couch comprising a seat, a swinging back, shiftable arm rests and links pivotally connected to both ends thereof and pivotally connected with the structure below the seat whereby the arm rests are shiftable into different positions according to the position of the back.
15. A convertible chair couch comprising a seat, a swinging back pivotally connected with the seat, a shiftable foot, automatically shiftable arm rests, and a pair of links pivotally connected to the arm rests at opposite ends thereof and pivotally connected with the structure independently of the seat and of the pivotal connection of the back and seat and adjustable into lowered position when the back is lowered to form a couch.
16. A convertible chair couch comprising a seat, a swinging back, shiftable arm rests, links pivotally connected to both ends thereof and pivotally connected with the structure below the seat whereby the arm rests are shiftable into different positions according to the position of the back, and means co-operating with a link pivotally connected to the rear end of an arm rest for holding the back in any of its adjusted positions.

Signed at Brooklyn, New York, this 10th day of September, 1928.

JUDSON L. MCKELLAR.
